SHIRT PROTECTING DEVICE

Reynolds Guyer and Russell J. Hennessey, St. Paul, Minn., assignors to Waldorf Paper Products Company, St. Paul, Minn., a corporation of Minnesota

Application March 27, 1942, Serial No. 436,482

2 Claims. (Cl. 223—71)

Our invention relates to an improvement in shirt reinforcing members and in a method of producing the same, wherein it is desired to simplify the procedure of producing the shirt stiffening elements and to lower the cost of production.

When garments, such as men's shirts for example, are laundered they are ordinarily provided with a reinforcing element of cardboard, or the like, which is folded or enclosed within the folded shirt so as to hold the same in a flat condition. It is also common practice to provide stiffening elements of cardboard, or the like, which may be placed within the collars of the shirts to keep the collars from becoming creased or wrinkled before they are worn. These collar reinforcing elements are ordinarily an entirely separate article from the shirt stiffening means used to hold the body of the shirt in a flat folded shape.

It is the object of the present invention to provide a shirt reinforcing element which may be of the usual rectangle shape, from the center of which is stamped and is removably supported the collar reinforcing element for the shirt. This construction has several advantages. In the first place, less cardboard is used, as the collar reinforcing element is removed from the central portion of the shirt stiffening board. The removal of this collar reinforcing element from the stiffening board does not materially weaken the stiffening board and does not change the outer conformation thereof. At the same time the collar reinforcing element need not be stamped or cut from a separate sheet as is usual practice.

A further feature of the present invention lies in the provision of a band designed to encircle the shirt so as to hold the shirt in a folded condition. This band may also be cut from the body of the shirt stiffening board so as to save material. The band is usually formed of material cut from the central portion of the stiffening element so as not to change the outer shape of the stiffening board. Even when both the collar reinforcing element and the encircling band have been cut from the body of the stiffening board, the effectiveness of the board has been found not materially reduced.

A further feature of the present invention lies in the provision of a band which is so designed that it may be readily cut from the central portion of the stiffening board. The stiffening board is usually rectangular in shape and the width of the board is ordinarily substantially greater than half the length of the board. As a result, a single band cut from the body of the board would not be of sufficient length to encir-

cle the shirt. Accordingly, we have produced a novel type of encircling band which is of a length not greatly in excess of the width of the board, so that this band may be easily cut from the center of the stiffening board without materially detracting from the effectiveness of the board.

A further object of the present invention lies in the provision of a novel type of collar reinforcing element. Most of the reinforcing elements used within the collars of shirts when they are shipped from the factory, or when they are returned from the laundry, are arcuate in shape so as to readily bend into a frustro-conical shape. We have found that by properly folding a straight strip of cardboard or similar material, the proper form of reinforcing element may be constructed from this straight strip. Such a construction is advantageous, not only because the straight strip may be more easily cut from the stiffening board, but also because a smaller portion of the board is affected when the strip removed from the board is straight from end to end.

A further feature of the present invention lies in the provision of a collar reinforcing element having a pair of wings foldably secured thereto designed to engage the outer surface of the forward points of a shirt collar to hold the collar points in proper position. With the folded collar reinforcing element of our design, these wings actually engage the outer surface of the collar points and effectively hold these collar points in proper position.

Our invention relates not only to the construction of the collar reinforcing element and shirt encircling band, but also to the method of forming these elements from the stiffening board, as this method greatly reduces the cost of these elements.

A further feature of the present invention lies in the provision of a shirt stiffening board having a shirt collar reinforcing element partially cut therefrom. The reinforcing element and the stiffening board are connected by short uncut portions of the board. The stiffening board may also be provided with a shirt encircling band partially cut therefrom, but being supported to the stiffening board by short uncut portions of the board. As a result the process of preparing the shirt for the customer is greatly simplified. For example, the same stiffening board may be used for shirts with or without an attached collar. If the stiffening board is to be used with a shirt having an attached collar, the collar reinforcing member is torn from the stiffening board and placed in position to reinforce the shirt collar. If the stiff-

ening board is to be used for a shirt which has not attached collar, the collar reinforcing element may be disregarded and left attached to the stiffening board. Similarly the encircling band may or may not be removed from the stiffening board during the preparation of the shirt for the customer.

These and other objects and novel features of our invention will be more clearly and fully set forth in the following specification and claims.

In the drawings forming a part of our specification:

Figure 1 is a perspective view of a shirt having an encircling band, a collar reinforcing element, and a stiffening board from which the band and reinforcing element are removed.

Figure 2 is a plan view of the stiffening board showing the encircling band and collar reinforcing element attached thereto before removal for use.

Figure 3 is a plan view of a stiffening board showing a collar reinforcing element of somewhat usual construction removably provided therein.

Figure 4 is a plan view of a shirt stiffening board showing the collar reinforcing element of our novel construction removably attached thereto.

Figure 5 is a plan view of the collar reinforcing element shown in Figure 4 after removal from the stiffening board.

Figure 6 is a plan view of a collar reinforcing element of a slightly different type from that shown in Figure 5, but embodying the principles of our invention.

Figure 7 is a top plan view of the collar reinforcing element when folded into proper form to reinforce the shirt collar.

Figure 8 is a view similar to Figure 7 showing a modified form of construction.

Figure 9 is a plan view of one form of shirt encircling band.

Figure 10 is a perspective view of the band illustrated in Figure 9 when folded into operative position.

Figure 11 illustrates a modified form of shirt encircling band before folded into encircling shape.

Figure 12 is a perspective view of the band illustrated in Figure 11 when folded into shirt encircling condition.

Figure 13 is a plan view of a modified form of shirt encircling band.

Figure 14 is a perspective view of the band illustrated in Figure 13 in shirt encircling position.

The shirt A is shown in Figure 1 as embodying a shirt stiffening board B of the usual rectangular outline shape, and illustrates a collar reinforcing element C and a shirt encircling band D which have been cut from the body of the stiffening member B. The shirt stiffening board B, with the reinforcing element C and the band D, are best illustrated in Figure 2 of the drawings, in which figure the reinforcing element C and the band D are integrally attached to the stiffening board B.

The stiffening board B comprises a flat sheet of cardboard, or the like, indicated in general by the numeral 10, which is shown rectangular in outline shape. While the outline shape of the stiffening board may be varied if desired, these boards have usually been formed in the rectangular shape illustrated.

The collar reinforcing element C is best illus-

trated in Figure 5 of the drawings. This element C comprises an elongated strip 11. At or near the center of the strip 11 a pair of fold lines 12 and 13 are provided therein, which fold lines converge together at a point 14 which may be the center point of the strip. The fold lines 12 and 13 each extend in a slanting direction from the center point 14 at a substantially equal angle to the edge of the strip so as to define a central isosceles triangle 15. The divergent ends of the fold lines 12 and 13 are preferably cut or slit at 16 and 17 so that the base of the triangle 15 is separated from the remainder of the strip. The slits or cut portions 16 and 17 extend a substantial distance toward the point 14 for a purpose which will be hereinafter more clearly set forth.

When the strip 11 is to be used for reinforcing a collar it is folded into the position best illustrated in Figure 7 of the drawings. The strip ends 19 and 20 are folded back along the fold lines 12 and 13 so as to assume the angle formed by the neck band of the shirt. Because of the fact that fold lines 12 and 13 are in angular relation to the upper edge 21 of the band 11, the ends 19 and 20 are inclined. Thus when the collar reinforcing element B has been folded into the position illustrated in Figure 7, this element may underlie the opposite sides 22 and 23 of the collar of the shirt A to prevent the sides of the collar from wrinkling or creasing.

In inserting the collar reinforcing element B in place within the shirt collar, it will be noted that the triangular portion 15 between the strip ends 19 and 20 extends at a considerable angle to the surface of the shirt which it engages. Accordingly as the reinforcing element is inserted the lower end or base of the triangular portion 15 will ordinarily fold along a line 24 connecting the upper extremities of the slits or cut portions 16 and 17. This action will permit the reinforcing element to be inserted a considerable distance beneath the shirt collar and the base of the triangle will engage against the front surface of the shirt, thus frictionally holding the reinforcing element from slipping out of place. In other words, not only do the slits 16 and 17 permit the lower edges of the band 11 to curve to some extent to better fit the shape of the collar, but also the edge 25 of the base of the triangle will engage against the surface of the shirt to hold the collar reinforcement in place.

In Figure 2 of the drawings, it will be noted that the reinforcing element C is not entirely cut from the sheet 10, forming the shirt stiffening board B. Short uncut portions, indicated at 28, are provided to hold the strip 11 secured to the sheet 10. As a result, if the shirt being prepared for the customer is not of the collar attached type, this stiffening element may remain an integral part of the board 10 and need not be detached therefrom. On the other hand, the collar reinforcing element C is readily available for use and may be quickly torn out of place when desired for use.

Figure 3 illustrates a shirt stiffening board E, which incorporates a different type of collar reinforcing element, illustrated in general by the letter F. The shirt stiffening board E comprises the sheet 28 of cardboard, or the like, from which is cut or stamped the collar reinforcing element F. The element F is arcuated in shape, as illustrated, and comprises a curved strip 27, which is connected to the body of the board 28 by short uncut connecting portions 29. The strip 27 will bend into a frustro-conical surface so as to fit beneath the collar of a shirt to reinforce the same.

In Figure 4 of the drawings, I disclose a stiffening board G, which is similar to the board B, with the exception that only the collar reinforcing member C is stamped or cut therefrom. The stiffening board G includes a body portion 30 from the central portion of which is stamped or cut the collar reinforcing element C. Short uncut portions 31 connect the element C to the body of the bolt 30.

In Figure 6 of the drawings, I disclose a collar reinforcing element which may be used in place of the reinforcing element B where it is desired to provide wings for retaining the points of the collar in place. This collar reinforcing element, indicated in general by the letter H, comprises an elongated strip 32, which is cut or stamped from the central portion of the shirt stiffening board, such as B or G. The element H is provided with a pair of score lines or fold lines 33 and 34, which converge toward a point 35 on the upper edge 36 of the strip. The fold lines 33 and 34 diverge from a point 35 in a manner to form a triangular portion 37, somewhat similar to the triangular portion 15 of the reinforcing element C. The element H, however, is provided with a pair of ears or wings 39 which extend transversely from the fold lines 34. These wings 39, being divided by slits or cuts 40 in the strip 32. As a result when the ends 41 and 42 of the strip 32 are folded into proper form to fit beneath the sides 22 and 23 of a shirt collar, the wings 39 engage against the outer surface of the sides of the collar to hold the collar points in place. A fold line 43 is provided between the triangular portion 37 and the wings 39 to allow these wings to extend over the outer surface of the collar while the ends 41 and 42 of the strip extend within the collar.

It will be seen that because of the relative dimensions of the shirt stiffening board it would not be possible to cut a single length strip sufficiently long to encircle the shirt. We have found, however, that by forming this band as best illustrated in Figures 9 and 10 of the drawings, an effective shirt encircling strip may be provided.

The band D is formed of an elongated strip 44 of cardboard or the like, which may be cut or stamped from the central portion of the stiffening board as best illustrated in Figure 2 of the drawings. It will be noted that the strip 44 is secured to the body of the sheet 10 by short uncut portions 45 which will permit the strip to be readily torn from the stiffening board B when desired for use.

The strip 44 is provided with two scored lines or fold lines 46 and 47 each of which is parallel to and adjacent an end of the strip. Extending between these fold lines 46 and 47 we provide a pair of spaced parallel slits 48 and 50. These slits 49 and 50 are centrally connected by a transversely extending slit 51. This structure provides two parallel bands 52 and 53 between which are provided a pair of opposed strip portions 54 and 55. Near the abutting ends of the strip portions 54 and 55 we provide interlocking slots 56 and 57 which enable the ends of the strip portions 54 and 55 to be interlocked together as best illustrated in Figure 10 of the drawings.

A pair of fold lines 59, parallel to the fold line 46 and adjacent the same, are provided through the strips 52 and 53, and single fold or score lines 60 are provided in these strips parallel to and adjacent the fold line 47. This permits the strips 52 and 53 to extend in offset relation to the interlocked strip portions 54 and 55 in the manner best illustrated in Figure 10 of the drawings. Thus, in

finished form a structure is provided in which interlocked band portions 54 and 55 lie on one plane, while the bands 52 and 53 lie in a parallel plane so that the body of the shirt may be supported between the bands 52 and 53 and the interlocked band portions 54 and 55.

In Figures 11 and 12 we disclose a modified form of band construction. This form of construction is somewhat similar to that previously described. The band J is in the form of an elongated strip 61 which is provided with fold lines 62 and 63 parallel to and adjacent the ends of the band. A slit 64 extends between the fold lines 62 and 63, dividing the band longitudinally. A transverse slit 65 separates one side of the strip 61 into two band portions 66 and 67, while the other side of the strip comprises a single band 69. A fold line 70 is provided in the band 69 parallel to and adjacent the fold line 62 and a second transverse fold line 71 is provided parallel to and adjacent the fold line 63. The band portions 66 and 67 are provided with interlocking slots 72 and 73 by means of which the band portions 66 and 67 may be interlocked.

When the band J is in operative position the band 69 may extend over the front of the shirt and the ends of the band 69 are terminally connected to the band portions 66 and 67. The band portions 66 and 67 are interlocked at their ends to form a loop designed to encircle the body of the shirt.

Another form of band construction is illustrated in Figures 13 and 14 of the drawings. In this form of construction the band K is in the form of an elongated strip 73 of cardboard, or the like, which may be stamped or punched from the body of the shirt stiffening board B similarly to the manner in which the band D is cut therefrom. The strip 73 is provided with a longitudinally extending slit 74 which extends most of the length of the band 73, but which terminates at a point spaced from the ends thereof. The strip 73 is divided by the slit 74 into two parallel strips 75 and 76 which are connected at both ends and the strip 76 is slit transversely at 77 to divide the strip 76 into two sections. A tape 79 may be provided projecting from one of the two strip portions into which the strip 76 is divided and this tape 79 may be used to connect the ends of the separated portions of the strip 76 after the strip 76 has been bent to lie in a plane parallel to the plane of the strip 75. In other words, a loop is formed in the manner best illustrated in Figure 14 of the drawings, which is capable of encircling the body of the shirt.

While we have shown numerous specific examples of forms of construction which may be used, it should be noted that all of these constructions are similar in that in each case the band or collar reinforcing element is punched or cut from the shirt stiffening board. As a result a saving in material is effected and the shirt may be prepared for the customer in an extremely short period of time due to the fact that all of the elements are furnished separately connected together.

In accordance with the patent statutes, we have described the principles of construction and operation of our method and apparatus for reinforcing a shirt, and while we have endeavored to set forth the best embodiments thereof, we desire to have it understood that these are only illustrative of a means of carrying out our invention and that obvious changes may be made

within the scope of the following claims without departing from the spirit of our invention.

We claim:

1. A shirt encircling band comprising an elongated strip of flexible material, a pair of substantially parallel slits in said band extending longitudinally thereof and terminating in spaced relation to the ends of the strip thus forming three parallel bands terminally connected by unslotted portions; one of said bands being cut in two intermediate its ends, fold lines transversely of said strip at the ends of said slits, the cut ends of said one band being folded along said fold lines to overlie the opposite side of said unslotted portions from the remaining bands, second transverse fold lines in said other bands in spaced parallel relation to said first fold lines, said bands forming a substantially rectangular ring when the cut ends of said one band are in overlapping relation.

2. A shirt encircling band comprising an elongated strip of flexible material, an elongated slit extending longitudinally of said strip and terminating short of the ends of the strip, providing a pair of bands terminally connected by an unslotted portion, transversely extending fold lines across said strip at the ends of said slit, one of said bands being cut intermediate its ends, the cut ends of said band being folded over said unslotted portion to position said unslotted portion between said one band and the other band, and second fold lines transversely across the other of said bands, in spaced parallel relation to said first fold lines to form a substantially rectangular ring when the cut ends of said one band are overlapped.

REYNOLDS GUYER.
RUSSELL J. HENNESSEY.
